UNITED STATES PATENT OFFICE.

RODERICK H. WILLCOX, OF COLUMBUS, OHIO.

VEHICLE DOOR-FASTENER.

1,079,969.

Specification of Letters Patent.

Patented Dec. 2, 1913.

Application filed March 22, 1913. Serial No. 756,096.

To all whom it may concern:

Be it known that I, RODERICK H. WILLCOX, a citizen of the United States, residing at Columbus, in the county of Franklin and 5 State of Ohio, have invented certain new and useful Improvements in Vehicle Door-Fasteners, of which the following is a specification.

My invention relates to vehicle doors and 10 is particularly directed to an improvement in doors slidably mounted upon the vehicles.

It is aimed to provide a door of this type which will prevent the bothersome rattle thereof when the vehicle is in motion. 15 Various endeavors have been made along this line and my invention aims to provide a structure for binding the door against movement in a manner that will prevent its rattle. To this end, I have provided a 20 trackway and a friction member binding therewith, operable from either the inside or the outside of the vehicle. This structure may be used as a locking means for the door itself and in this event the door may be 25 held locked in any adjusted position and automatically releasable upon movement of the operating handle.

Another object of my invention is to provide an operating handle for freeing the 30 door out of its frictional binding, that is operable in either a forward or backward movement. This structure permits the ready manipulation of the door from either an open or closed position.

35 The preferred embodiment of my invention is shown in the accompanying drawings, in which similar characters of reference designate corresponding parts, and in which:

40 Figure 1 is a longitudinal section of a common type of vehicle having a slidable door and showing my invention applied thereto, Fig. 2 is a section taken on line 2-2 of Fig. 1, Fig. 3 is a slightly enlarged side 45 view of my invention shown applied to the vehicle, Fig. 4 is a detail view of the operating end of the friction member, Fig. 5 is an end view of my invention looking from the right of Fig. 3, Fig. 6 is an enlarged 50 view taken on line 6-6 of Fig. 3, and, Fig. 7 is a detail view of a portion of the operating handle used by me.

In the drawings, I have shown a common type of vehicle comprising sides 1, top 2, dash 3, seat structure 4 and slidable door 5. 55 The door 5 is suspended from the trackway 6 by the brackets 7 carrying the usual roller construction 8. Adjacent the lower edge of the doors are provided brackets 9 bent to hook shape, as shown, to coöperate with the 60 side boards 10 of the vehicle bed and thereby prevent lateral movement of the doors. However, when moving along the road, these doors will inevitably rattle and to guard against this, I have provided a track- 65 way 11, preferably of hollow semi-circular form, securely attached to the base board of the seat structure. A rod 12 is designed to be carried by the door 5 and to be held in frictional binding relation with the 70 trackway 11, thereby serving both as a means of locking the door in any adjusted position and also as a means for the prevention of the rattle, by forcing the rollers 8 tightly against their trackway 6. The 75 friction rods 12 should be carried in a line parallel with the trackway 11 and this I do by the provision of two brackets 13 securely fastened to the side of the door and pierced at their upper ends as at 14, for the pivotal 80 reception of links 15 which are in turn pivotally connected to depending pierced lugs from the underside of the rod 12, all as shown at 16. Each of the rods 12 also carries a bent finger 17 adapted to form a hook 85 for one end of the coiled spring 18, which is permanently attached at its opposite end to the vehicle door as shown at 19. The spring 18 is normally slightly extended and thereby exerts a forward pull upon the rods 90 12 and thereby forcing them into binding relation with their trackways 11 through the medium of the links 15. It will also be noted that these links 15 are normally slightly inclined and thereby prevent moving of the rods 12 past their dead center. 95

The operating handle 20, shown in detail in Fig. 7, is provided with an angular portion 21 adapted to be passed through the door body and securely held in place there- 100

on. The extremity of the angular portion 21 is also provided with a squared portion 22 and a threaded extremity 23. This squared portion 22 is adapted to pass 5 through a square aperture in the body portion 24 of the complementary handle 25 carried upon the inside of each vehicle door. It will be noted that the body portions 24 extend a considerable distance below the 10 point of support 26 of these handles and that they are adapted to abut one end of the friction rods 12. It will, therefore, be noted that movement of the handle portion 25 toward the right as indicated by the dash 15 lines in Fig. 3, will cause a rearward movement of the friction rods 12, also shown in dash lines, and that these rods are thereby moved out of engagement with their complementary trackways 11. This movement 20 will, however, be natural only when the door 5 is moved from its open position to its closed position. In order to accommodate the natural tendency of a person when opening the door, to pull the opening lever toward himself or, if a knob, to give such 25 knob a right-handed turn, I have provided each of the rods 12, with a right angular upward extension 27 adapted to extend upward a distance slightly above the supporting 30 points 26 of the inside handles. It will, therefore, be noted that movement of the handle portions 25 to the left will also cause movement of the friction rods 12 to the position shown in dash lines by the coaction 35 of the upward extensions 27 with the upper portions of the body portions 24 of the inside handles. In order to prevent dislodgment of the upward extensions 27, I have provided each of the inside handles with a 40 guard plate 28 which serves as a confining medium for these extensions.

It will be apparent that movement of the inside handles as outlined above, will cause an additional tensioning of the springs 18 45 and that, therefore, the friction rods 12 will be automatically returned to their operative position upon release of these inside handles. It will also be apparent that the doors themselves may be adjusted upon their 50 trackways to various positions and that they will in all these positions, be securely held in position by the provision of the binding structure outlined, this binding structure having the additional function of preventing 55 their rattle while the vehicle is in motion.

What I claim, is:

1. In combination with a slidably mounted vehicle door, means for frictionally binding said door against movement, an operating handle, means connected with said operating handle and operable by operation of the handle for rendering said binding action ineffective to allow free movement of the door, and means for automatically re-

establishing said binding action upon release of said handle. 65

2. In combination with a slidably mounted vehicle door, means for frictionally binding said door against movement when in any position, an operating handle, means 70 connected with said operating handle and operable by the operation of the handle for rendering said binding action ineffective to allow free movement of the door in either direction, and means for automatically re-establishing said binding action upon release of said handle. 75

3. In combination with a slidably mounted vehicle door, a trackway mounted on the vehicle body, a friction member adapted for 80 coöperation with said trackway normally frictionally binding the door against movement, and means for moving said member bodily away from said trackway to permit movement of the door. 85

4. In combination with a slidably mounted vehicle door, means for frictionally binding said door against movement, a pivoted handle element, and means controlled by said handle element in its movement in either 90 a forward or backward direction to render said binding action ineffective to allow free movement of said door.

5. In combination with a slidably mounted vehicle door, a trackway mounted on the 95 vehicle body, a friction member carried by said door and coöperating with said trackway, a handle element pivoted to said door, and means controlled by said handle element in its movement in either a forward 100 or backward direction to render said friction member ineffective.

6. In combination with a slidably mounted vehicle door, a hollow semi-circular trackway mounted on the vehicle body, a 105 rod friction member coöperating with said trackway, link connections between said rod and said door, a spring for forcing said rod in engagement with said trackway, and a handle element pivoted to said door and operable either by a forward or backward movement to force said rod out of engagement with said trackway and against the tension of said spring. 110

7. In combination with a slidably mounted vehicle door, a trackway mounted on the vehicle body, a rod friction member coöperating with said trackway, a spring for forcing said rod in engagement with said trackway, a handle element, and means for moving said rod as a whole out of engagement with said trackway by operation of said handle. 115

8. In combination with a slidably mounted vehicle door, means for frictionally binding said door against movement, a handle portion, a bar to which said handle portion is connected intermediate its ends, and a 120 125

bar extension lying parallel with and abutting said first mentioned bar, such last mentioned bar being operatively connected to said frictionally binding means whereby
5 the binding action is relieved by either a forward or reverse movement of said handle portion.

In testimony whereof I affix my signature in presence of two witnesses.

RODERICK H. WILLCOX.
